UNITED STATES PATENT OFFICE.

WILLIAM W. MOWRY, OF ST. LOUIS, MISSOURI.

CHECK-INDORSING MACHINE.

1,195,068.

Specification of Letters Patent. Patented Aug. 15, 1916.

Application filed December 9, 1912. Serial No. 735,639.

To all whom it may concern:

Be it known that I, WILLIAM W. MOWRY, citizen of the United States, residing at St. Louis, in the State of Missouri, have invented a certain new and useful Improvement in Check-Indorsing Machines, of which the following is a full, clear, concise, and exact description.

My invention relates to printing mechanism.

The particular embodiment of the invention which I have selected as illustrating the novel features thereof has been devised primarily as an improvement in apparatus for marking or indorsing checks. Accordingly some of the features hereinafter described are directed mainly toward a machine of the character indicated, whereas other features are of broader application and are not thus limited.

Bank checks are customarily indorsed by hand by striking the successive checks with a rubber stamp. Machines have been proposed heretofore for lightening the manual labor involved by substituting automatic means for performing this function. Such machines usually involve either a reciprocating stamp or a printing couple in the form of a pair of rolls, one of which has raised type thereon adapted to imprint the customary indorsement on the back of the check as it is fed between said rolls. It has been found difficult to feed the checks by hand at the proper time to receive the indorsement in the proper place on the check. As a result, in many instances, only a portion of the indorsement appears near one edge of the check and in still further cases the arrangement is such that the indorsement appears at right angles to the proper direction. Frequently one indorsement has been superimposed on another, whereby neither are legible.

An additional disadvantage has been that all checks are not indorsed to the same bank in the course of a day and it becomes necessary to change the characters on the printing roll. This substitution has proved troublesome and difficult to perform without soiling the fingers with ink.

The object of my invention, generally speaking, is to provide apparatus in which the above and other difficulties are obviated.

As contributory toward carrying out the general object enumerated, I have, as further objects to provide a machine in which the

elements of the printing couple are normally out of contact with each other but are intermittently brought together, said movement being controlled by the passing of a check between said elements; to provide means for feeding the check to the printing roller in properly timed relation to the rotation thereof, whereby the check is always indorsed in the middle; to provide means whereby the indorsement may be made to appear at any predetermined distance from the end of the check; to provide a printing element having type or characters which may be readily interchanged in order to change the indorsement on the checks; to provide an improved inking roller; and to provide a machine which is rapid and automatic in its operation, which does not require any particular skill or training on the part of the user, which is relatively simple in construction, and which embodies numerous refinements in the organization thereof.

In the accompanying drawings I have shown the following views of a machine which represents what I consider to be the preferred design.

Figure 1 is a section elevation on the line 1-1 of Fig. 2; Fig. 2 is a top, plan view; Fig. 3 is a partial end elevation; Fig. 4 is a sectional elevation on the line 4-4 of Fig. 2; Fig. 5 is a side elevation of certain of the parts shown in Fig. 4, but in a different relative position; Fig. 6 is a side elevation of the feed rolls; Fig. 7 is a similar view with the parts moved to a different position; Fig. 8 is a longitudinal, sectional elevation of the combined ink reservoir and roller; Fig. 9 is a side elevation of one of the feed rolls showing the details thereof; Fig. 10 is a side elevation of the impression roll; and Fig. 11 is a sectional elevation on the line 11-11 of Fig. 10.

The machine comprises a suitable frame having a base 1 and side walls 2, 2 between which the printing mechanism is mounted. The checks to be indorsed are conveniently stored on a suitable table or shelf 3 arranged at the upper part of the machine and toward the front thereof, the rear part of said shelf being hinged whereby it may be swung up to permit access to the underlying mechanism. The checks are placed in small piles on the supports 4 in which they stand in such a manner that the individual checks may be quickly lifted one at a time and dropped into a hopper, the

- latter comprising suitable guide plates 5, 5 and an adjustable end plate 6. The checks are guided by the walls of said hopper between a printing couple consisting of a printing member 7 and a bed member 8, both having the form of rolls.
- Each check, as it is dropped between the guides, does not necessarily pass between the printing couple immediately, but, as hereinafter described, is restrained momentarily and automatically advanced at such a time that the raised characters on the printing roll will be impressed against the back of the check. Furthermore the printing roll and the bed roll are normally out of contact and are brought into contact only momentarily as the check is passing between them, thereby keeping the surface of the latter free of ink. Said checks, after passing said rolls, are guided by the chute 9 into a receptacle or tray 10 arranged at the lower part of the machine and at the front thereof, into which they fall face side down, whereby the accumulated checks when removed are arranged in the same order as before indorsing. The chute 9 has ribs raised from the base thereof (see Fig. 1), whereby friction between the check and the base of the chute is decreased.
- The printing roll 7 is fixed to the main shaft 11 and rotates therewith, the latter being driven continuously by a motor 12, through suitable connection described later. An auxiliary shaft 13 is also provided, both of said shafts being rotatably mounted in the side walls 2 of the frame. The bed roll 8 is carried on the shaft 13, said roll having the form of a hollow cylinder loosely surrounding a second cylinder 14 which is eccentrically mounted on the shaft 13, but does not turn therewith. As seen in Fig. 4, the position of said eccentric cylinder with respect to said shaft is such that the bed roll is normally out of engagement with the printing roll, there being a considerable clearance between the two. Said rolls may be brought in contact, however, by a partial rotation of the eccentric roll as hereinafter described. The main shaft 11 has mounted thereon outside of the end wall 2 a disk 15 which is driven by a friction disk 16, the latter bearing also against the armature shaft 17 of the motor 12 and being driven thereby. The friction disk 16 is maintained in close frictional engagement with said shaft 17 and said disk 15 by means of its supporting yoke 18 which is loosely secured by a pin 19 to the main frame and yieldingly drawn to the rear by a suitable spring 20 as seen in Fig. 3. Hence, the main shaft is driven by said motor through said friction drive, the auxiliary shaft being driven from the main shaft by suitable pinions 20, 21 mounted on the other ends of said respective shafts as seen in Fig. 2.
- A series of feed rolls or friction wheels 22, 23 are mounted on the shafts 11 and 13 and rotate continuously therewith. Said rolls, which are arranged in pairs, as in Figs. 6 and 7, are disposed at intervals along said shafts. As said friction rolls are always rotating in contact with each other, it is apparent that if a check were fed directly to them said check would immediately be moved past the printing roll 7. The checks are not fed directly to said friction rolls, however, but after being dropped between the guide plates 5, 5 are prevented from reaching said feed rolls by fingers or arms 24 having preferably the form of rods which project across the bottom of the hopper through openings or notches 25, 26 in the lower edge of said guide plates 5, 5 as seen in Fig. 2, thereby obstructing the downward movement of the check. Said fingers 24 are yieldingly mounted, being secured to a rotatable rod 27 which carries an arm 28 to which is secured a light spring 29, the latter being adjustably secured at its opposite end to a fixed support 30. The tension of the spring is preferably such that the fingers 24 will be maintained in normal position, against the weight of the check which tends to force them aside, said tendency being very slight, of course. Said tension is insufficient, however, to resist the downward movement of the check if the same is seized and forced toward the feed rollers.
- In view of the delicacy of the above adjustment I provide positive locking means for maintaining said fingers in normal position except during certain intervals when it is desirable that they shall be free to yield. Said means in the preferred form comprises a locking rod 31 which projects from the shaft 27, preferably near one end thereof, (see Figs. 1 and 2), said rod resting against a shoulder on the locking plate 32, the latter being pivotally supported on the pin 33 and normally held against a suitable stop 34 by a spring 35. Said plate is provided with a projecting pin 36 which is adapted to be engaged by the beveled edge 37 of the extremity of an arm 38 secured to the shaft 11 so as to rotate therewith. During every revolution of said shaft the pin 36 is raised slightly by being engaged by said beveled edge 37 thereby rocking the plate 32 and releasing the rod 31 which, however, ordinarily remains in the same position due to the pull of the spring 29, although otherwise free to fall away from said lock.
- As previously stated, the downward movement of the check is arrested by the fingers 24 which fingers may be pushed aside if the check is seized and forced downward. I provide suitable means for advancing the check in this manner at such a time during the rotation of the printing roller 7 that the

raised characters thereon will bear against the check substantially centrally with respect to the long edges thereof. Said means may assume various forms.

5 In Figs. 6 and 7 I have illustrated fingers 39 one of which is carried by each of the feed rollers 22 and 23. As these fingers are alike a description of one will suffice for all. Referring to Fig. 6, the finger 39 is 10 mounted on the roll 22 being pivotally supported at the point 40 and held in normal position against a stop 41 by a suitable spring 42. Said fingers are so arranged that during each revolution of the feed 15 rolls 22, 23 they abut against each other and while in contact move downwardly from the position shown in Fig. 6 to that shown in Fig. 7 at which point they separate, the line of contact being substantially 20 tangential to the feed rolls. Said fingers as they come together in the position as shown in Fig. 6 are adapted to seize the check between them and draw the same downwardly far enough to enable it to be 25 seized by the friction rolls 22 and 23 which insure its passing through the printing couple, as shown in Fig. 5. Although the fingers 39 maintain only a frictional hold on the opposite sides of the check, said hold is 30 sufficient to draw down the check and cause the latter to force the arms 24 to one side against the action of the spring 29.

After the fingers 39 separate, as they are about to do in the position shown in Fig. 35 7, they would be thrown outwardly against their respective stops 41 by the action of their springs 42, thereby tending to produce a hammering noise when the machine is in operation. To obviate the hammering 40 the finger 39, secured to the friction roll 41, is provided with a projecting pin 43 which engages a cam surface 44 on a plate 45 just as the pair of fingers are about to separate as shown in Fig. 7. Said cam surface is 45 substantially the arc of a circle arranged eccentrically with respect to the shaft 12 so that by the time the pin 43 rides off of said cam surface the arm has been gradually moved up to and against the stop 41. The 50 same arrangement is provided for the finger on the feed roller 23, a cam surface 46 being formed on a suitable plate 47. This arrangement not only does away with hammering but it insures the release of the 55 check by said fingers as soon as it is gripped between the feed rolls.

As soon as the check is seized by the feed rolls 22 and 23, it is desirable to bring the bed roller 8 into yielding engagement with 60 the printing roller 7. This movement is accomplished indirectly through the slight rocking of the shaft 27 when the fingers 24 are pushed aside by the descending check. Said shaft is provided with an arm 48 (Fig. 65 4) which normally bears against the link

49, which is pivoted at 50 and normally held against stop 51 by the action of a spring 52, the tension of the latter being sufficient to overcome the tendency of the arm 48 to rock said link about its pivot. 70 A latch 53 is suitably secured to the eccentric roll 14 and is engaged in a notch in said lever 49 being held in position by a suitable spring 54. The rocking of shaft 27, however, swings the arm 48, thereby moving the link 49 rearwardly and disengages the latch 53 which is thereupon drawn down by the spring 54 to the position shown in Fig. 5, thus giving a partial rotation to the eccentric roll 14 and causing the bed roll 8 75 to exert a yielding pressure against the face of the check which by this time has started to pass between said rollers.

It will be seen that there is normally a considerable clearance between the rolls 85 comprising the printing couple and that as soon as the check starts to pass between them actual contact between the two is prevented by said check, whereby no ink from the printing roller ever reaches the surface 90 of the bed roller. Said rolls are separated prior to a complete rotation of the printing roll by the restoration of the latch 53, said latch being restored by a pin 55 projecting from the side of one of the adjacent feed 95 rolls (the latter being shown in Fig. 2 but not in Figs. 4 or 5), which pin raises an arm 56 which is pivotally supported at the point 57 and is provided with a pin 58 which latter lifts the latch 53 until it is engaged in the notch in the link 49. From the above description it will be seen that the relative movement of the elements of the printing couple toward and away from each other is automatically controlled by the advance of successive checks.

The feed rollers 22 and 23 may be constructed in various ways. In the preferred construction, the roll 22 comprises a disk of any suitable material with a rim 60 of rubber. The roll 23 may be similarly constructed, but I preferably employ a block 61 of suitable material to which is secured a plurality of rings or hoops 62 of steel or other resilient material. Each ring is secured at 110 one end to said block, the other end being free, as shown in Fig. 9, said free ends being arranged at different points circumferentially to insure a continuous cylindrical surface. The resilient material permits the 115 necessary frictional hold to be maintained even after the surface of the opposite roll wears away to an appreciable extent and renders one pair of rolls more or less independent of the other pair. For example, if 120 a check is passing through, to which is pinned certain extra memorandum sheets, one or more of the metal feed rolls would yield the desired amount, the remaining 125 wheels perhaps not yielding perceptibly. 130

The printing roller comprises a block 63 of suitable material to which is secured a metallic plate 64 by means of screws 65 which pass through slots 66 therein (Fig. 10). Said plate has projecting finger grips 67 whereby it may be moved back and forth to move the locking projection 68 into and out of engagement with corresponding projections 69 on a curved plate 70, the latter being secured also by the turned in edge 71 which engages a ledge on said block 63 (Fig. 11). The plate 70 carries suitable characters preferably in the form of a rubber base 72 having raised type thereon. By the removal of the plate 70 the indorsement may be readily changed. Said plate is preferably provided with an opening 73 which enables it to be fitted over suitable type 74 indicating the date, the latter being wedged in a transverse slot in the block 63, and requiring to be changed only once a day. Access to the printing roller is had by raising the hinged portion of the plate 3 as indicated in Fig. 1.

The position of the printing roller is, of course, fixed with respect to the side frames 2. It is necessary, however, to indorse the checks in different places, that is at different distances from the ends of said checks in view of existing indorsements thereon. In order to cause the machine to imprint its indorsement at a predetermined distance from the end of the check, the guide plate 6 previously referred to is suitably adjusted along its supporting shaft and the checks, as they are dropped into the hopper, are positioned against this guide plate. By the use of said plate an improved method of automatically indorsing checks may be carried out to obviate the printing of one indorsement on the top of another. This method consists in assigning to each of the larger cities,—New York, Chicago, Philadelphia, St. Louis—for example, a certain space or zone at a predetermined distance from the end of the check. With this understanding the guide plate 6 may be suitably adjusted so that all checks stamped by New York, for example, are indorsed in a certain zone. Even in the absence of this provision if the application of ink to the printing roll can be suitably regulated, so as to make a light impression, the indorsements will be legible even though one is occasionally superimposed on one another. The means for regulating the ink supply in the desired manner is hereinafter described.

Ink is supplied to the printing roller by a combined ink roller and reservoir 75 which is mounted on an arm 76 pivotally supported at 77 and maintained in normal position by a spring 78 the tension of which may be adjusted by the stud 79. Said ink roller (see Fig. 8) consists essentially of a spirally arranged element preferably of

rubber covered wire 80 through the adjacent spirals of which the ink is adapted to be admitted to the outer covering of felt 81 or other absorbent fabric the latter being covered over properly with cambrie to form 70 a suitable inking surface. The ends of said coil are suitably secured in end pieces 82, 82 preferably of resin, said end pieces being backed up by retaining washers 83 connected by a perforated cylindrical element 84 75 which surrounds said spiral element. The pin or bearing member 85 is secured to the left hand washer 83 and an adjusting screw 86 is rotatably secured to the right hand washer 83, by means of arms 87 which fit 82 in an annular groove therein. A hollow shaft or tube 88 communicates with the interior of the reservoir and is provided with a spline 89 which is received in a suitable slot in the washer 83 whereby said tube 85 which is secured at its inner end in the resin disk, may be moved outwardly to relax the pressure between the adjacent coils of the covered wire. This outward movement is caused by rotation of the adjacent nut 86, said nut having screw threaded engagement with said tube. The cap 90 which is screwed over the outer end of said tube is adapted to act also as a bearing. Thus the reservoir, which is removable from its supports, may be readily filled with ink by removing the cap, and the flow of ink to the absorbent material may be regulated to a very fine degree, to give a light, distinct impression when indorsing the checks. 95

It will be apparent, in view of the introductory statements, that the invention is not to be limited to the particular embodiment of the invention described herein or to the various phases thereof, as numerous changes may be made and other embodiments may be designed which fall within the scope of the invention. Accordingly I desire to cover suitable equivalent means for accomplishing the desired result wherever said means fall within the scope of the appended claims. 100

What I claim is:

1. In a machine of the character described, the combination with a printing couple comprising a continuously-rotating printing member and a bed-member normally at rest out of operative relation to said printing member, of feed rolls for feeding a sheet of paper to said printing couple, means revolving with said printing member and operating in timed relation thereto for advancing a sheet of paper to said feed rolls, and means, actuated by the advance of the sheet of paper, for moving said bed-member into operative relation with said printing member. 115

2. In a machine of the character described, the combination of a printing couple comprising a continuously-rotating 120

125

130

- printing cylinder and a rotatable bed-cylinder normally at rest out of operative relation to said printing cylinder, yielding restraining means normally preventing the 5 advance of sheets of paper to said printing couple, means operating in timed relation to the rotation of said printing cylinder for causing said restraining means to yield to permit of the advance of a sheet, and means, 10 actuated by the yielding of said restraining means, for moving said bed-cylinder into operative relation to said printing cylinder.
3. In combination, a printing couple comprising a pair of rolls between which sheets 15 of paper may be advanced, means yieldingly mounted to prevent said advance, a lock for preventing the yielding of said means, said lock being periodically rendered inoperative by a continuously rotating driving element, and means for forcibly advancing said sheets past said yielding means during the intervals when said lock is inoperative.
4. In a check-indorsing machine, a printing couple comprising a printing cylinder and a bed cylinder, an eccentrically mounted roll on which said bed cylinder is mounted, said cylinders being normally out of contact with each other, means for rotating said roll to bring said cylinders into contact, feed rolls for advancing a check to said printing couple, and yielding devices controlled by the advance of said check to said feed rolls for permitting the operation 30 of said means.
5. In a machine for imprinting indorsements on checks, a printing roll and a bed roll, said bed roll being mounted on an eccentric cylinder, a spring which tends to 35 rotate said cylinder and move said rolls into contact with each other, means for holding said cylinder in normal position against the action of said spring, and a latch for releasing said means, said latch being operated by the advance of a check toward 40 said rolls.
6. In a machine for imprinting indorsements on checks, a printing roll and a bed roll, said bed roll being mounted on an eccentric cylinder, a spring which tends to 45 rotate said cylinder and move said rolls into contact with each other, means for holding said cylinder in normal position against the action of said spring, a latch for releasing said means, said latch being operated by the 50 advance of a check toward said rolls, and means for restoring said parts to normal position after said check has passed said rolls.
7. A check indorsing machine comprising a printing couple consisting of coöperating rolls, supporting shafts therefor, guides for directing the checks to said printing couple, yieldable means normally obstructing the advance of said checks, a positive lock preventing the yielding of said 55 obstruction, means rotating with one of said shafts for periodically rendering said lock inoperative, and feed rollers on said shafts having means for forcing said checks past said obstruction during said periods.

In witness whereof, I, hereunto subscribe my name this third day of December, A. D., 1912.

WILLIAM W. MOWRY.
